(57) **CLAIM**

(**) Term: **15 Years**

The ornamental design for an angled grip, as shown and described.

(21) Appl. No.: **29/556,400**

DESCRIPTION

(22) Filed: **Feb. 29, 2016**

FIG. 1 includes a perspective view of a forward lighting system.

(51) LOC (10) Cl. **22-01**

FIG. 2 includes a first side view thereof.

(52) U.S. Cl.

FIG. 3 includes a second side view thereof.

USPC **D22/108**

FIG. 4 includes a front view thereof.

(58) **Field of Classification Search**

FIG. 5 includes a rear view thereof.

USPC D22/108; 42/90, 94, 114, 117, 124, 125,

42/126, 127, 131, 146; 362/109, 110,

362/111, 112, 113, 114

FIG. 6 includes a bottom view thereof; and,

CPC F41C 23/10; F41C 23/14; F41C 23/16;

FIG. 7 includes a perspective view of a firearm with an angled grip.

F41C 23/18

See application file for complete search history.

The broken lines in the figures depict portions of the angled grip that form no part of the claimed design. The broken line depiction of a rifle in FIG. 7 forms no part of the claimed design.

(56) **References Cited**

The angled grip finds use as an accessory for firearms, paintball guns, and other projectile weapons.
